UNITED STATES PATENT OFFICE.

LOUIS C. WALKER, OF DAYTON, OHIO.

BALL-COURT.

SPECIFICATION forming part of Letters Patent No. 437,267, dated September 30, 1890.

Application filed August 8, 1889. Serial No. 320,102. (No model.)

To all whom it may concern:

Be it known that I, LOUIS C. WALKER, a citizen of the United States, residing at Dayton, in the county of Montgomery and State of Ohio, have invented a new and original Ball-Court to be Used in a Game of Ball; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to a ball-court used in playing ball.

The novelty of my device consists in the manner of scoring and counting points in the game and the general arrangement of the 20 parts.

In my device cords suspending bars are so arranged as to form square spaces, within which spaces thus formed are suspended from the bars differently-painted balls—one 25 for each square—to represent numbers, and the whole suspended between trestles, and batted balls striking the suspended balls or passing through the spaces so formed, and the scoring of points represented by the balls 30 hit. An outer court formed the same way around three sides of the court proper constitute my ball-game.

The object of my invention is to secure a ball-game to be played, preferably, on a lawn, 35 that will be interesting and enjoyable for children or grown people. I attain this object by the mechanism shown by the accompanying drawings, in which—

Figure 1 represents a perspective view of 40 my ball-court suspended between trestles; Fig. 2, a form of bat that may be used in the game.

Similar letters and figures refer to similar parts throughout the several views.

45 In the drawings, A A represent trestles suitably constructed, fastened to the ground by guy-ropes c c, and connected by supporting cross-beam B. To cross-beam B are suspended, by means of cords a a a, placed at convenient distances apart, bars b b b placed at 50 convenient distances apart on the cords to form square spaces. Within these spaces

thus formed are suspended from bars B b b balls 1 1 1 1 1 1 1, painted of different colors to represent numbers, or numbered, as 55 wished, to indicate the points to score when hit. At either side of the court thus formed, at convenient distance from the court to cross-beam B, are suspended, by means of cords a' a', bar b', below the court, to form 60 an outer court around the three sides of the ball-court proper. A batted ball passing through this outer court scores a loss of any agreed number of points to the batter.

C is an ordinary flat wooden paddle of any 65 desired size to hit the ball. I prefer to ornament this paddle by painting diagonal stripes across its flat faces to represent the ordinary lawn-tennis racket.

In this game, by means of bat C, balls are 70 hit and thrown through the spaces of the ball-court and the scores counted according to which of the balls 1 1 1 1 1 1 1 are hit, or the number counted representing the space through which the batted ball passes. If the 75 ball passes through the outer court, a loss of points agreed upon is scored. The suspended balls and spaces may represent any number of points agreed upon.

Having sufficiently described my invention, 80 what I claim, and desire to secure by Letters Patent, is—

1. In the game described, the combination, with trestles and a cross-bar mounted thereon, of a series of vertical cords suspended 85 therefrom, horizontal bars connected with and suspended by the cords, a series of vertical cords suspended from the cross-bars, and counters connected with the last-named cords, as set forth. 90

2. In the game described, the combination, with trestles and a cross-bar mounted thereon, of a series of vertical cords suspended 95 therefrom, horizontal bars connected with and suspended by the cords, a series of vertical cords suspended from the cross-bars, counters connected with the last-named cords, and an outer court consisting of cords and a cross-bar, as set forth.

LOUIS C. WALKER.
